PRODUCTION OF ORGANIC ACIDS

Martin Luther and Hans Franzen, Mannheim,
Germany, assignors to I. G. Farbenindustrie
Aktiengesellschaft, Frankfort - on - the - Main,
Germany, a corporation of Germany

No Drawing. Application April 5, 1929, Serial
No. 352,901, and in Germany April 14, 1928

2 Claims. (Cl. 260—122)

The present invention relates to the production of pure fatty acids.

5 The fatty acids obtained by the oxidation of solid waxes, such as paraffin and like waxes, contain considerable quantities of dark colored compounds, such as hydroxycarboxylic acids, lactones and inner esters, and when employed in soap-making, or for other conversions, yield soaps and the like which are dark in color.

10 We have now found that the dark colored compounds can be eliminated from these oxidation products in a surprisingly simple manner and pale fatty acids obtained, by subjecting the crude products to a pressing treatment at a temperature below the melting point of the pure acids. Under this treatment the dark colored impurities become liquefied but not the fatty acids, so that the two components are separated. The pure fatty acids so obtained are pale in 15 color, have substantially higher melting points than the crude product, and furnish pale soaps. In the pressing process the application of a slightly elevated temperature is often of advantage.

20 25 The following example will further illustrate the nature of the invention, which however is not restricted thereto.

Example

30 1000 parts of crude fatty acids, with the melting point 35° to 38° centigrade obtained by oxidizing hard paraffin wax treating the product

with an excess of a saponifying agent and recovering the fatty acids from the resulting soaps, are cooled to 12° to 13° centigrade, packed into press cloths and subjected to a pressure of about 100 atmospheres in a hydraulic press. The liquid portion, about 450 parts, consists of a dark colored oil, whilst the solid portion, about 550 parts, consists of hard, pale fatty acids, with a melting point from 45° to 48° centigrade which, when employed for soap-making, furnish a pale 65 soap.

What we claim is:—

1. In the process of recovering pure saturated fatty acids from the crude acids obtained by hydrolysis of the soaps produced by saponification of the products resulting from the oxidation of paraffin wax, the step which comprises subjecting said crude acid reaction portion to mechanical pressure at a temperature below the melting point of the saturated fatty acids contained therein.

2. In the process of recovering pure saturated fatty acids from the crude acids obtained by hydrolysis of the soaps produced by saponification of the products resulting from the oxidation of paraffin wax, the step which comprises subjecting said crude acid reaction portion to a pressure of about two atmospheres at a temperature of about 12°-13° centigrade.
